CLAIM

The ornamental design for combined fuel pump display and hose retractor assembly, substantially as shown and described.

DESCRIPTION

FIG. 1 is a top front perspective view of a combined fuel pump display and hose retractor assembly showing my new design, with the fuel pump shown in broken lines for illustrative purposes only;

FIG. 2 is a side elevational view thereof;

FIG. 3 is a top plan view thereof;

FIG. 4 is a bottom plan view thereof;

FIG. 5 is a front elevational view thereof, the rear elevational view being a mirror image thereof; and

FIG. 6 is a top front perspective view thereof.
